DESIGN FOR A HAND DRILL

Francesco Collura, New York, N. Y., assignor to
Millers Falls Company, Greenfield, Mass., a
corporation of Massachusetts

Application January 6, 1945, Serial No. 117,306

Term of patent 14 years

(Cl. D54—4)

To all whom it may concern:

Be it known that I, Francesco Collura, a citizen of the United States, whose post-office address is 425 East 51st Street, New York city 22, county and State of New York, have invented a new, original, and ornamental Design for a Hand Drill, of which the following is a specification, reference being had to the accompanying drawing, forming a part thereof.

Fig. 1 is a side elevational view of a hand drill showing my new design;

Fig. 2 is a front elevational view thereof; and

Fig. 3 is a bottom plan view looking toward the lower end of the drill as illustrated in Fig. 1.

I claim:

The ornamental design for a hand drill, as shown.

FRANCESCO COLLURA,
